UNITED STATES PATENT OFFICE.

RUFUS H. ROSE, OF NEW YORK, N. Y.

DESIGN FOR A HANDKERCHIEF.

SPECIFICATION forming part of Design No. 18,469, dated July 17, 1888.

Application filed June 16, 1888. Serial No. 277,376. Term of patent 3½ years.

To all whom it may concern:

Be it known that I, RUFUS H. ROSE, a citizen of the United States, residing at New York, in the county of New York and State of New York, have invented a certain new and useful Design for Bandanas; and I do hereby declare the following to be a full, clear, and exact description of the invention, such as will enable others skilled in the art to which it applies to make and use the same.

The drawing represents an ordinary handkerchief of silk, cotton, or other suitable fabric.

A represents the body of a handkerchief or other like manufacture, and B B the figures thereon.

The leading feature of my design consists in a handkerchief having upon its surface a series of patterns, as shown, each representing a snuff-box, the central box being somewhat larger than those surrounding the same. 20

What I claim is—

The design for a handkerchief having the surface configuration herein shown and described.

In testimony whereof I affix my signature in presence of two witnesses.

RUFUS H. ROSE.
